[57] CLAIM

The ornamental design for a child's carrying case, as shown and described.

DESCRIPTION

FIG. 1 is a front elevational view of a child's carrying case showing my new design;

FIG. 2 is a rear elevational view with the handle extended;

FIG. 3 is a left side elevational view thereof, the right side being a mirror image of the left side shown;

FIG. 4 is a top plan view;

FIG. 5 is a bottom plan view; and

FIG. 6 is an external elevational view of the case in its fully open position;

FIG. 1

FIG. 2

FIG. 3

FIG.4

FIG.5

FIG. 6
